UNITED STATES PATENT OFFICE.

JOHN L. KAHLES, OF OAKLAND, CALIFORNIA.

DESIGN FOR A COMBINED TIME-TABLE, ADVERTISING BOARD, AND CLOCK.

54,927.

Specification for Design.

Patented Apr. 20, 1920.

Application filed January 9, 1917. Serial No. 141,488. Term of patent 7 years.

To all whom it may concern:

Be it known that I, JOHN L. KAHLES, a citizen of the United States, residing at Oakland, in the county of Alameda and State of California, have invented a new, original, and ornamental Design for a Combined Time-Table, Advertising Board, and Clock, of which the following is a specification, reference being had to the accompanying drawing, forming part thereof.

The figure is a face view of the combined

time table, advertising board and clock showing my new design.

I claim:

The ornamental design for a combined time table, advertising board and clock as shown.

JOHN L. KAHLES.
